UNITED STATES PATENT OFFICE.

JAMES C. FRENCH, OF CHICAGO, ILLINOIS, ASSIGNOR TO FREDERICK C. AUSTIN, OF CHICAGO, ILLINOIS.

SWINGING-SCOOP EXCAVATOR.

Application filed January 26, 1918. Serial No. 213,868.

To all whom it may concern:

Be it known that I, JAMES C. FRENCH, a citizen of the United States of America, and resident of Chicago, county of Cook, and State of Illinois, have invented a certain new and useful Improvement in Swinging-Scoop Excavators, of which the following is a specification.

This invention relates to swinging scoop excavators of that general class in which a scoop is mounted on the lower end of a beam which is pivoted on the outer end of a swinging boom and in which means are provided for operating said beam and boom, to fill the scoop and to then raise the boom into position for the load, and for controlling the scoop to discharge the contents thereof when the desired dumping position is reached.

Generally stated, the object of the invention is to provide a novel and improved swinging scoop excavator of the foregoing general character.

A special object is to provide an improved construction and arrangement whereby the scoop is caused to fill or take up a load by movement thereof toward the body of the excavator, and whereby the boom and the beam upon which the scoop is mounted can then be raised to carry the load upward to the desired dumping position.

It is also an object to provide certain details and features of construction and combinations tending to increase the general efficiency and desirability of an excavator of this particular character.

To the foregoing and other useful ends the invention consists in matters hereinafter set forth and claimed.

In the accompanying drawings:

Figure 1 is a side elevation of the body portion of an excavator embodying the principles of the invention, showing one end thereof, and also the swinging boom, broken away and omitted for convenience of illustration.

Figure 2 is a side elevation of the boom and its pivoted beam and scoop.

Figure 3 is a view similar to Figure 2, but showing the full length of the boom, and illustrating the beam and scoop in dumping position.

Figure 4 is a plan of the scoop, on a larger scale, and of a portion of the boom, being a horizontal section on line 4—4 in Figure 2.

Figure 5 is a front elevation of said scoop, 55 showing the lower portion of the tilting beam.

Figure 6 is an enlarged detail sectional view of one of the locking devices for the scoop.

As thus illustrated, the invention comprises a body or main frame 1 mounted on a suitable turn-table 2, which latter is supported by a truck comprising caterpillars 3, one at each side of the machine, of any suitable length, so that the excavator is self-propelled by means of a truck upon which the body frame is supported through the medium of a turn-table, whereby said body can be turned or rotated about a vertical axis. 70 It will be understood that the other end portion of the body frame 1, which is shown broken away, may be equipped with an engine or motor for operating the caterpillars or other traction devices, and for operating 75 the winding-drum-mechanism 4 by which the various lines or cables are operated or controlled to in turn operate or control the excavating apparatus. Said apparatus comprises a boom 5 pivoted on the body frame at 80 6, whereby this boom may swing up and down. At its outer end, said boom is provided with a beam 7 which is pivoted on the end of the boom at 8, so that this beam may

tilt about a transverse axis at the outer end 85 of the boom. At its lower end said beam 7 is provided at its inner side with a transverse head 9 to one end of which the scoop 10 is pivoted at 11, said scoop facing the body frame of the excavator, whereby the scoop 90 must be filled by forward movement thereof toward the body of the excavator. To hold the scoop in operative position on the head 9, locking devices are provided, each comprising a locking bolt 12 in a barrel 13, 95 which latter contains a spring 14 to keep the locking bolt yieldingly extended. The mouth of the scoop is provided with a pair of catches 15 to engage the outer ends of said locking bolts, and the relative formation of said catches and locking bolts (see Figure 6) is such that when the scoop swings upward about its pivot 11 these catches 15 will engage the bolts 12 and force the latter inward or backward against the yielding 105 pressure of the spring 14, before the bolts shoot into the openings 16 of said catches, which latter will lock the scoop in operative

position on the head. To withdraw said locking bolts, thereby to release the scoop, when it is desired to dump the load, a rock-shaft 17 is mounted transversely on the head 9 and provided with arms 18 which are suitably connected with rods 19 connected with the locking bolts, whereby rocking motion of this shaft will withdraw the bolts 12 from engagement with said catches. This is preferably accomplished through the medium of a crank-arm 20 on the rock-shaft 17, and by means of a tripping cable or line 21 secured to this arm and extending upward and over the sheave 22 on the outer end of the boom, and then back to the winding-drum mechanism 4, if it be desired to operate it by power, or, if desired, simply to a position where it can be operated by hand to control the locking mechanism of the scoop when it is desired to release or dump the load. The head 9, it will be seen, is held practically at right angles to the beam 7 by means of a brace 23 connected to the outer end of said head. Another line 24 is connected to the mouth of the scoop at 25, and extends upward and over a sheave 26 on the head 9, then over the sheave 27 on the outer end of the boom 5, then back to the winding-drum mechanism 4, whereby, after the load is dumped, a pull may be exerted on this line or cable 24 to restore the scoop to operative position on the head 9, the previously described locking mechanism serving automatically to lock the scoop in this raised or restored position. In addition, the forward end of the head 9 has a sheave 28 for engaging the operating cable or line 29, the latter being fastened at one end to the base of the boom at 30, and then, after passing around said sheave, passing under the sheave 31 at the base of the boom and then upward to the winding-drum mechanism 4, whereby the latter may be operated to pull the scoop forward from the position in which it is shown in dotted lines in Figure 3, thereby to cause it to take up a load. Thus the line 29 serves like a drag line to operate the bucket. The upper end of the beam 7 is provided with a pivoted link 32, which is adjustably connected therewith, and which is in turn connected with a shorter link 33 pivoted on the boom, the joint between these two links being provided with a sheave 34 for the line or cable 35 by which the boom 5 is raised and lowered. This line or cable 35 may be arranged in any suitable or desired manner, and may, for example, have one end thereof secured to the main body frame at 36, and can then pass around the sheave 34 and back to the sheave 37 on the upper portion of the main body frame, and then downward to the winding-drum mechanism 4, so that the latter may be operated to raise and lower the boom. It will be seen that, with this arrangement, a pull exerted by the winding-drum mechanism 4 on the cable or line 35 will exert a pull on the link 32, and will thus produce, or tend to produce, a tilting motion of the beam 7, so that the latter will be tilted outward into the position shown in dotted lines in Figure 3, whereby the scoop is then in position to be lowered into the ground, or into a loose mass of materials, to thereafter be pulled forward to take up a load. This operation of the scoop is produced, as previously described, by the operating line or cable 29, and when the beam 7 reaches the tilted position shown in full lines in Figure 3, or substantially so, the scoop is then in position to safely carry the load upward and around into the dumping position.

Obviously, there are various ways of using an excavating machine, or a machine for handling materials, of the foregoing construction, and the invention is not limited to any particular use or method of use. For example, the boom 5 can be lowered to bring the scoop into position for operation, on the ground, or in a mass of loose materials, such as coal, crushed rock, sand or gravel, and the cable or line 29 can then be operated to pull the scoop forward, thus causing it to receive a load. Then, while maintaining a sufficient pull on the line or cable 29, to keep the scoop in carrying position, the cable or line 35 can be operated to swing the boom 5 upward, and thereafter, if necessary, the turntable mechanism 2 may be operated, by any suitable power-transmitting connection with the engine or motor on the body of the machine, to swing the boom 5 laterally to the extent necessary to carry the scoop around to the desired dumping position. Then the tripping rope or cable 21 will be operated, either by hand or by power, thus unlocking the scoop, and allowing it to tilt into the position shown in full lines in Figure 3, thereby discharging the load. For this dumping operation it will be necessary, of course, to ensure a slack condition of the restoring rope or cable 24, so that the downward tilting motion of the scoop into dumping position will not be retarded. As soon, however, as the load is discharged this line or cable 24 can then be operated by the winding-drum-mechanism, to restore the scoop to operative position on the head 9, as previously explained, thereby to automatically lock the scoop in raised or operated position, so that it will then be ready for another operation after being lowered to the ground. Of course, if the scoop is not exactly in position to take up the load, the caterpillars or other traction devices 3 can then be operated to move the scoop bodily forward, in unison with the entire structure of the machine, thus bringing the scoop into position for operation, or pulling it directly into the mass of loose materials, if necessary, so that it

will take up a load. With this construction, therefore, the scoop may be moved or operated in a direction to take up a load by the cable or line 29, while the entire weight of 5 the scoop and the boom and the beam is exerted downward, and without any tendency to lift the scoop. There is no lifting action whatever until the line or cable 29 is operated.

10 With the construction shown and described, it will be seen that the bucket is positively tilted up and down about its pivot 11 on the beam 7, so that it is released or tripped to dump the load, and is then 15 positively raised into latched position on the beam, so that it is ready for operation when lowered to the ground.

With the construction shown and described, it will be seen that the drag-line 20 29 is connected through the locking device or latch 12 and 15 to the scoop, so that the pull on the drag-line is exerted through said locking device to the scoop to pull the latter along the ground, when the scoop is loaded. 25 In this way, means are provided for, in effect, connecting the drag-line to and disconnecting it from the scoop.

What is claimed as my invention is:

1. In a traveling excavator, a boom, a beam pivoted on the outer end of said boom, 30 a scoop pivoted on the lower end of said beam, means to raise and lower said boom, instrumentalities including means for controlling the scoop to cause the up and down 35 tilting thereof on said beam and other means for operating said scoop to take up a load and discharge the same therefrom, including a drag line leading directly to a point at the mouth of the bucket, and means 40 to hold the scoop rigid with the beam at all times except when tilted to dump the load.

2. In a swinging scoop excavator, a boom, a beam pivoted on the outer end of said boom, a transversely disposed head on the 45 lower end of said beam, a scoop pivoted on one end of said head, a latch to lock the mouth of the scoop to the other end of the head, means to raise and lower said beam, instrumentalities for controlling and operating 50 said scoop to take up a load and discharge the same therefrom, and a body frame to support said boom, said scoop being disposed in position for movement toward said body frame to take up a load,

55 and said instrumentalities including one line for pulling the scoop forward, a second line to trip the latch and release the load, a third line to restore the scoop to operative position at the lower end of said beam, 60 means on the lower end of said beam to support the one line, and means on the boom to support the second and third lines.

3. A structure as specified in claim 1, said beam having a link mechanism pivotally connected to the upper end thereof, and said 65

lifting means being connected to said link mechanism, whereby operation of said means to lift the boom serves also, after the drag line is released to tilt the beam on its pivot to carry the scoop backward and 70 outward into position to again be pulled along the ground by the drag-line when the boom is lowered.

4. A structure as specified in claim 2, said beam having a parallel motion link mechanism pivotally connected to the upper end thereof, the second and third lines extending around the pivot of said beam and under said mechanism, and said lifting means being connected to a joint of said 75 link mechanism, whereby operation of said means to lift the boom serves also to tilt the beam on its pivot.

5. In a swinging scoop machine, the combination of a boom pivotally mounted at 80 one end to swing up and down, means whereby the boom may also swing sidewise, a vertically disposed beam pivoted on the outer end of said boom, a pivot on the lower end of said beam, a transversely arranged 85 head having one end mounted on said pivot, a brace connecting the other end of said head with said beam, so that said head is rigid with the beam and extends toward the pivoted end of the boom, a scoop having 90 its rear end mounted on said pivot and its mouth or front end disposed toward the pivoted end of said boom, means for locking the scoop against the under side of said head, a releasing line for controlling said 95 locking means, means carried by said boom to support said line, a restoring line for pulling the scoop upward into locked relation to said head, means carried by said boom to support said second line, means 100 connected to the end of said head and operating like a dragline to pull the scoop forward along the ground and toward the pivoted end of the boom for causing the scoop to take up a load, and devices for raising 105 and lowering the boom and tilting said beam thereon.

6. A structure as specified in claim 5, said devices comprising a short link pivoted on the boom, a long link adjustably pivoted on 110 the upper end of said beam, with a pivotal connection between the two links, and a raising and lowering line connected to said links, said releasing and restoring lines extending around the pivot of said boom and 115 under said long link.

7. In an excavator, the combination of a boom, a vertically disposed beam pivoted on the end of said boom, means for tilting the beam about its pivot, a scoop pivoted 120 on the lower end of said beam, with the mouth of the scoop facing toward the excavator, means for tilting the scoop about its pivot, a drag-line extending directly to a point at the mouth of said scoop, means for 125

raising and lowering said boom, and means for releasably locking the scoop against movement relatively to said beam, said locking device being interposed between the 5 scoop and said drag-line, so that the drag-line is connected through the lock to the scoop.

8. In an excavator, the combination of a support, a scoop disposed on the bottom 10 of said support, a pivot for the rear end of the scoop at the rear end of the support, a catch on the front end of said support, means on the front end of said scoop to engage said catch, a swinging beam to the 15 lower end of which the support is rigidly fixed, means to operate said beam, and means to release said catch to dump the load.

9. In an excavator, the combination of 20 a scoop, a drag-line for pulling the scoop forward along the ground, a support on which the scoop is pivoted, and means including a locking device through which the drag-line is connected to the scoop, and by

which the scoop is locked against movement 25 relatively to said support.

10. A structure as specified in claim 10, in combination with means to control said locking device, and means to tilt the bucket about its pivot on said support. 30

11. A structure as specified in claim 10, in combination with means for pivoting said support to swing about a horizontal 35 axis, and means for controlling said support.

12. The combination of a scoop, a drag-line for operating the scoop along the ground, and means for, in effect, connecting the drag-line to the scoop and for disconnecting it therefrom. 40

13. A structure as specified in claim 13, said means comprising a locking device, in combination with a line to control said locking device, and another line to control the 45 scoop.

Signed by me at Chicago, Cook County, Illinois, this 18th day of January, 1918.

JAMES C. FRENCH.
